CAR LOADING CONVEYER

John R. Madeira, Chicago, Ill., assignor to Goodman Manufacturing Company, Chicago, Ill., a corporation of Illinois

Application December 30, 1943, Serial No. 516,159

5 Claims. (Cl. 214—42)

This invention relates to improvements in conveyers, and more particularly relates to a new and improved means for continuously transferring loose material from a main line conveyer into a train of mine cars with a minimum amount of spillage.

The principal object of my invention is to provide a novel form of material transferring means for continuously transferring material from the discharge end of a main line conveyer into a traveling train of mine cars, which consists in a relatively short transfer conveyer mounted beneath the discharge end of the main line conveyer and extending transversely thereof in a direction parallel to a mine trackway, for receiving material from said main line conveyer and selectively transferring it from either of its ends onto mine cars on said trackway, together with an efficient and novel form of rapidly reversible drive connection from said main line conveyer to said transfer conveyer, designed to facilitate the loading operation and to minimize the spilling of material from the ends of the cars during loading.

A more specific object of my invention is to provide a transfer conveyer beneath the discharge end of a main line belt conveyer and to drive this transfer conveyer from the belt conveyer through a rapidly reversible drive connection including a plurality of constantly meshing gears, and a plurality of friction disk clutches, for connecting said gears to drive said transfer conveyer in reverse directions without reversing the direction of travel of said main line conveyer, so said transfer conveyer may continuously load a train of cars traveling along a trackway, from either of its ends, without spilling material at the gaps between the cars.

Other objects of my invention will appear from time to time as the following specification proceeds and with reference to the accompanying drawings wherein:

Figure 1 is a plan view of a loading device constructed in accordance with my invention, showing the transfer conveyer in position to load into either one of two mine cars of a train of mine cars;

Figure 2 is an enlarged view in side elevation of the discharge end of the main line conveyer, with certain parts of the transfer conveyer shown in transverse section;

Figure 3 is a view looking towards the discharge end of the main line conveyer, drawn to substantially the same scale as Figure 2 and showing certain parts of the transfer conveyer in longitudinal section;

Figure 4 is an enlarged plan view showing certain details of the drive from the main line conveyer to the transfer conveyer; and

Figure 5 is an enlarged sectional view taken substantially along line 5—5 of Figure 4, illustrating certain other details of the drive from the main line conveyer to the transfer conveyer than are shown in Figure 4.

In the drawings, the embodiment of my invention illustrated is shown as including a main line conveyer 10 extending along a mine entry and having a transfer conveyer 11 at its receiving end, extending transversely of said main line conveyer, for loading material into mine cars 12, 12 on a track 13, disposed therebeneath and extending in the direction of travel of said transfer conveyer.

The main line conveyer 10 is herein shown as being a well known form of belt conveyer including a belt 14 movable along a frame 15 and around an idler 16, mounted at the discharge end of said frame. Said idler is mounted on a transverse shaft 17, suitably journaled at the discharge end of said frame and having a sprocket 18 keyed at one end thereof and forming a means for driving the transfer conveyer 11 from said main line conveyer, as will hereinafter more clearly appear as this specification proceeds.

The transfer conveyer 11 extends transversely of and is suspended from the mine roof and supported on the discharge end of the frame 15, and extends in a direction parallel to the mine track 13, for discharging material into the mine cars 12, 12 from either of its ends as said mine cars travel along said track. Said transfer conveyer includes a frame 19 having an inner side wall 20 and a laterally spaced outer side wall 21 (see Figure 2). A central stiffening and connecting member 22 of said frame connects the side walls 20 and 21 together and extends laterally beyond the outer side wall 21. Said connecting member has a depending leg 23 of a T-shaped suspending member 24 secured thereto. The cross of the T of said suspending member has a pair of angles 25, 25 secured thereto by bolts 26, 26. Said angles extend upwardly from said member, adjacent opposite ends thereof, and may be suitably connected to the roof supports of the mine at their upper ends, to form a support for the outer end of said transfer conveyer on said roof supports. Said bolts also extend through the upper side of a side wall 27 of a pan 28 of the conveyer to connect the upper end of said side wall to said suspending member. Said side wall extends vertically downwardly from its upper end, for a por-

tion of its height, and is then inclined inwardly and downwardly to the inside of the side wall 27, to form a retaining side wall for the transfer conveyer and to deflect material thereon. Said side wall then extends along the inside of the upper portion of the outer side wall 21, and turns horizontally inwardly to form a bottom 29 of said transfer conveyer. The opposite side of said panel extends upwardly along the inner side wall 20 to the top thereof and is then inclined in an upward direction towards the lower portion of the idler 16, to form an opposite retaining wall for said conveyer.

A pair of spaced supporting plates 30, 30 extend perpendicular to and inwardly from the inner side wall 20, along the lower flanges of channels 31, 31 of the frame 19 (see Figure 3). Said supporting plates are pivotally secured to support members 32, 32, extending along said lower flanges, parallel to the webs of said channels. Said support members are secured adjacent the outer ends of said lower flanges, as by welding, and project upwardly therefrom. Bolts 33, 33 having nuts threaded thereon are provided to detachably secure said plates 30, 30 to said members 32, 32 and to secure the inner side of said transfer conveyer to the discharge end of the frame 15 of said main line conveyer.

The material moving elements of the transfer conveyer 14 include a pair of endless chains 34, 34 having parallel flights 35, 35 connected therebetween. Said endless chains are trained around idlers 36, 36 at one end of the frame 19 and around drive sprockets 37, 37 at the opposite end of said frame. Said idlers are suitably journaled on a transverse shaft 38, which is slidably mounted in longitudinal guides 38, 39 formed in the side walls 20 and 21. Said guides open to the outer end of the conveyer frame for the insertion of said transverse shaft therein. Threaded members 40, 40 engaging opposite ends of said shaft, are provided to move said shaft along said guides, to adjust the tension of said chain in a usual manner. From said idlers said chains extend along the upper side of the bottom 29 of the panel 28, to and around the drive sprockets 37, 37 on a transverse drive shaft 43, journaled in the walls 20 and 21.

The means for driving the transfer conveyer 14 from the main line conveyer 10, in reverse directions without reversal of said main line conveyer, includes the sprocket 18 on the transverse idler shaft 17. A drive chain 50 meshes with and depends from said sprocket and is meshed with and drives a sprocket 51 on a shaft 53. Said shaft extends parallel to the shaft 17 and is journaled in a housing 54, extending from the inner side wall 20 in a direction towards the belt conveyer 10.

A take-up is provided for said chain, which includes an idler sprocket 55 rotatably mounted on a plate 56, which is slidably guided on the outer side of the support plate 30, which also forms an outer side wall of the housing 54. Said plate 56 is slidably moved along said side wall in directions to tighten or loosen said drive chain, in a manner well known to those skilled in the art, by means of a bolt 58.

The shaft 53 has a pair of bevel gears 59, 59 freely mounted thereon, adjacent the inner sides of opposite side walls of the housing 54. Said bevel gears mesh with a bevel gear 60 on the inner end of a transverse shaft 61. Said transverse shaft is journaled in suitable bearing supports mounted in the side walls 20 and 21, and

extends outwardly from said outer side wall 21 and has a spur gear 63 keyed to its outer end. Said spur gear meshes with a spur gear 64, on the conveyer drive shaft 43, for driving said shaft and the endless chains 34, 34.

A pair of friction disk clutches 65, 65 are provided to selectively connect either of the bevel gears 59, 59 with the shaft 61, to drive either of said gears from said shaft, so as to drive the transfer conveyer in reverse directions without reversal of the main line conveyer. Said friction clutches may be of any type which will take sudden loads and may be rapidly engaged and disengaged to rapidly reverse the direction of travel of said transfer conveyer, and are herein shown as being friction disk clutches of a well known construction. Each of said clutches includes a plurality of interengaging disks 66, 66, alternate of said disks being splined on a sleeve 69, keyed to the shaft 61, and the other of said disks being splined to the inner periphery of a drum 70 secured to and extending from the inside of an associate bevel gear 59. An engaging collar 71 is provided to engage said disks with each other. Said engaging collar is moved in a direction to engage said disks by means of a clutch collar 73, slidably mounted on said sleeve 69, for movement therealong. Said clutch collar has an engaging member 74 secured thereto and slidably mounted in a slot 75, extending along said sleeve 69. Said engaging member has rollers 76, 76 at its opposite ends, which are adapted to engage opposite engaging collars 71, 71, so as to move one of said collars in a direction to engage one friction clutch, and at the same time permit the opposite friction clutch to be disengaged, upon rectilinear movement of said engaging member along said slot in one direction or another. A clutch fork 77 is provided to shift said clutch collar 73 in one direction or another. The lower ends of the tines of said clutch fork are scribed and slidably engage pins 78, 78, projecting from opposite sides of the clutch collar 73. Said clutch fork is secured at its upper end to a rod 79, which is slidably mounted in opposite side walls of the housing 54. Said rod is slidably moved with respect to said housing to shift said clutchers by means of a rocking arm 80 secured to a rocking shaft 81, journaled in the inner side wall 20 adjacent one of its ends, and in the lower end of the leg 23 of the T-shaped supporting member 24, adjacent its opposite end. A hand lever 82 is mounted on the outer side of said rocking shaft, for rocking said shaft. Said rocking arm 80 has a bifurcated upper end, extending along opposite sides of the shifting rod 79, and having slidably engagement with a pin 83, mounted in said rod and projecting from opposite sides thereof.

It may be seen from the foregoing that during the loading operation, material may be discharged from the main line conveyer 10 onto the transversely disposed transfer conveyer 14, which extends in a direction parallel to the track 13 for discharging material from either of its ends into the mine cars 12, 12. Said transfer conveyer may be operated in one direction to load material in one mine car, and as the car is moving along the track, may be rapidly reversed to load material into the next succeeding mine car without spilling material in the gap between the two mine cars. As this mine car is being loaded as it travels along the track and its forward end passes beyond the advance end of said transfer conveyer, the direction of travel of said transfer conveyer may be rapidly reversed, to complete the loading

of said mine car. As said car continues to travel beneath said transfer conveyer, said conveyer may again be rapidly reversed, to fully load the car and evenly trim the car as it is passing under said transfer conveyer.

It may further be seen that the ability to instantaneously reverse said transfer conveyer under the control of the operator, in a simplified manner, insures full and continuous loading of the car passing beneath said transfer conveyer, with no spilling of material as the gaps between adjacent ends of the mine cars pass by either end of said transfer conveyer, and with no stopping of the main line conveyer or of the train of mine cars, during the loading operation.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In an apparatus for loading cars in mines, a main line conveyer extending along a mine passageway transversely to a mine trackway and having a discharge end disposed above said mine trackway, for loading material into cars on said trackway, and means for continuously transferring material from said conveyer into said cars during movement of said cars along said trackway, with a minimum amount of spillage, including a relatively short rapidly reversible transfer conveyer mounted on and disposed beneath the discharge end of said main line conveyer and extending transversely thereof, means for driving said transfer conveyer from said main line conveyer, said drive means including a reverse drive connection to said transfer conveyer including a pair of selectively operable friction clutches, operable to rapidly reverse the direction of travel of said transfer conveyer during travel of said main line conveyer in one direction, to enable the operator to rapidly reverse the direction of travel of said transfer conveyer while transferring the loading of material from one car to the other, so as to load onto the empty car during this transition period without spilling.

2. In an apparatus for loading cars in mines, a main line conveyer extending along a mine passageway transversely to a mine trackway and having a discharge end disposed above said mine trackway for loading material into cars on said trackway, and means for continuously transferring material from said conveyer into said cars during movement of said cars along said trackway, with a minimum amount of spillage including a relatively short rapidly reversible transfer conveyer mounted on and disposed beneath the discharge end of said main line conveyer and extending transversely thereof, means for driving said transfer conveyer from said main line conveyer in reverse directions without reversing the direction of travel of said main line conveyer, to enable the operator to rapidly reverse the direction of travel of said transfer conveyer while transferring the loading of material from one car to the other, so as to load onto the empty car during this transition period without spilling, including a transverse shaft, a geared drive connection from said shaft to said transfer conveyer, and a drive connection from said main line conveyer to said shaft including a shaft driven from

5 said main line conveyer, a pair of gears coaxial with said shaft, and a friction disk clutch associated with each of said gears for selectively connecting either of said gears with said last mentioned shaft, for driving said transfer conveyer in reverse directions while said main line conveyer continues to discharge thereon in one direction.

3. In an apparatus for loading cars in mines, a main line conveyer extending along a mine passageway transversely to a mine trackway and having a discharge end disposed above said mine trackway for loading material into cars on said trackway, and means for continuously transferring material from said conveyer into said cars during movement of said cars along said trackway, with a minimum amount of spillage including a relatively short rapidly reversible transfer conveyer mounted on and disposed beneath the discharge end of said main line conveyer and extending transversely thereof, means for driving said transfer conveyer from said main line conveyer in reverse directions without reversing the direction of travel of said main line conveyer, to enable the operator to rapidly reverse the direction of travel of said transfer conveyer while transferring the loading of material from one car to the other, so as to load onto the empty car during this transition period without spilling, including a transverse shaft, a geared drive connection from said shaft to said transfer conveyer, and a drive connection from said main line conveyer to said shaft including a shaft extending perpendicularly to said first mentioned shaft, a pair of bevel gears coaxial with one of said shafts and meshing with a bevel gear on said other shaft, and a pair of friction clutches for selectively connecting either of said bevel gears of said pair of bevel gears with its associated shaft, for selectively driving said transfer conveyer in reverse directions without reversal of said main line conveyer.

4. In an apparatus for loading cars in mines, a main line conveyer extending along a mine passageway transversely to a mine trackway and having a discharge end disposed above said mine trackway for loading material into cars on said trackway, and means for continuously transferring material from said conveyer into said cars during movement of said cars along said trackway, with a minimum amount of spillage including a relatively short rapidly reversible transfer conveyer mounted on and disposed beneath the discharge end of said main line conveyer and extending transversely thereof, means for driving said transfer conveyer from said main line conveyer in reverse directions without reversing the direction of travel of said main line conveyer, to enable the operator to rapidly reverse the direction of travel of said transfer conveyer while transferring the loading of material from one car to the other, so as to load onto the empty car during this transition period without spilling, including a transverse shaft, a geared drive connection from said shaft to said transfer conveyer, and a drive connection from said main line conveyer to said shaft including a shaft extending perpendicularly to said transverse shaft, a pair of bevel gears coaxial with said perpendicular shaft, a bevel gear on said transverse shaft meshed with said bevel gears, and a pair of friction clutches for selectively connecting either of said bevel gears with said perpendicular shaft, for selectively driving said transfer conveyer in reverse directions without reversal of said main line conveyer.

5. In an apparatus for loading cars in mines, a main line conveyer extending along a mine passageway transversely to a mine trackway and having a discharge end disposed above said mine trackway for loading material into cars on said trackway, and means for continuously transferring material from said conveyer into said cars during movement of said cars along said trackway, with a minimum amount of spillage including: a relatively short rapidly reversible transfer conveyer mounted on and disposed beneath the discharge end of said main line conveyer and extending transversely thereof, means for driving said transfer conveyer from said main line conveyer in reverse directions without reversing the direction of travel of said main line conveyer, to enable the operator to rapidly reverse the direction of travel of said transfer conveyer while transferring the loading of material from one car to the other, so as to load onto the empty car during this transition period without spill-

ing, including: a transverse shaft, a geared drive connection from said shaft to said transfer conveyer, and a drive connection from said main line conveyer to said shaft including: a shaft extending perpendicular to said transverse shaft, a chain and sprocket drive connecting said main line conveyer to said perpendicular shaft, two facing bevel gears freely mounted on said perpendicular shaft, a bevel gear keyed on said transverse shaft and meshing with said bevel gears, two friction disk clutches for selectively connecting either of said bevel gears with said perpendicular shaft, and means for selectively connecting said friction disk clutches in driving engagement with either of said bevel gears, for driving either of said bevel gears from said perpendicular shaft, and reversely driving said transfer conveyer without reversal of said main line conveyer.

JOHN R. MADEIRA.
